UNITED STATES PATENT OFFICE.

JAMES G. GREENE, OF ROCHESTER, NEW YORK, ASSIGNOR TO THE SINGER
MANUFACTURING COMPANY OF NEW JERSEY.

CLAMP FOR BUTTON-HOLE SEWING-MACHINES.

SPECIFICATION forming part of Letters Patent No. 319,700, dated June 9, 1885.

Application filed February 20, 1885. (No model.)

To all whom it may concern:

Be it known that I, JAMES G. GREENE, a citizen of the United States, residing at Rochester, in the county of Monroe and State of New York, have invented certain new and useful Improvements in Clamps for Button-Hole Sewing-Machines, of which the following is a specification, reference being had therein to the accompanying drawings.

10 My invention relates to that class of cloth or fabric clamps adapted to open or spread the button-hole after the fabric has been clamped, my object being to improve the construction of these devices so that their action will be 15 more positive and reliable, and thus lessen their liability to break or get out of order, as well as to add to their convenience.

In carrying my invention into effect I provide the base-plate of the cloth-clamp with 20 guides adapted to hold the lower plates or jaws of the clamp in place on said base-plate, but permitting said jaws to slide transversely of said plate a limited distance, the upper jaws of the clamp being mounted on the lower jaws 25 so as to slide therewith. The base-plate is provided with a recess in which is placed a slide provided with inclined ribs working in inclined grooves in the bottoms of the lower clamping-jaws, said slide being connected by 30 a link with an operating-lever. The backward or forward movements of the slide cause both sets of clamping-jaws to recede from or approach each other, these movements of said jaws being positive in both directions, and the 35 jaws remaining at all times parallel with each other, so as to spread the button-hole evenly its entire length. The upper clamping-jaws are pivoted or hinged to blocks carried by the lower jaws, and are operated to clamp or release the work by an arm or lever attached to 40 a small shaft having a crank connected by a link to a cross-bar engaging the arms of said jaws, the latter being thus operated positively in both directions. The operating-levers for the 45 spreading-slide and the upper clamping-jaws are preferably so arranged that they will both be moved in the same direction in clamping the goods and spreading the button-hole, so that both of these results may be effected by one

and the same movement of the hand of the operator.

In the drawings, Figure 1 is a plan view of a button-hole cloth-clamp embodying my invention, with the clamping-jaws together; and Fig. 2 is a similar view with the jaws moved 55 apart as in spreading the button-hole. Fig. 3 is a side view with the parts in the same position as in Fig. 2. Fig. 4 is a front end view. Fig. 5 is a side view, partly in section, with the upper jaws raised; and Fig. 6 a similar view with the upper jaws down, as in clamping. Fig. 7 is a top view of the base-plate and spreading-slide, and Fig. 8 a bottom view of the lower clamping-plate.

A indicates the base-plate of the clamp, and a and a' two sets of undercut parallel guides thereon, the former being removably attached to said plate.

B B are the lower clamping plates or jaws, having at their ends lips b, fitting beneath 70 similar overhanging lips, a², on the under-cut guides. The plates B are provided on their under sides with inclined grooves b'.

C is a spreading-slide movable in a recess, a³, in the base-plate A, and having inclined 75 ribs c, fitting easily in the grooves b' of the plates B. The slide C is connected by a link, d, with a lever, D, pivoted to an arm or bracket, e, of the post E, on the base-plate. through which post the guide-pin e² of the 80 clamp passes, said pin being normally depressed by a spring, e'.

F F are blocks rigidly secured to the plates B, and to the blocks F are hinged plates G, to which latter are rigidly secured the arms h of 85 the upper clamping-jaws, H, the arms h being preferably recessed into the plates G, as shown, and the jaws H being pivoted to said arms, as is usual.

I is a small shaft journaled in the blocks F, 90 and having a crank, i, connected by a link or pitman, J, to a cross-bar, K, slotted at its ends for the free passage of the arms h. The arms h are of spring-metal, as is usual in clamps of this kind, and the depth of the slots k in the ends of the cross-bar K is preferably considerably greater vertically than the thickness of said arms, so that the stress of the latter in 95

forcing the jaws H against the fabric may be varied by regulating screws k tapped in said cross-bar. L is an arm or lever attached to the shaft I, by which the latter may be operated to clamp or release the work.

The operation of my device is as follows: When the work is to be inserted, the upper clamping-jaws will be raised, as in Fig. 5, by lifting the lever L, and by moving said lever 10 forward and downward in the direction indicated by arrow 1 in Fig. 3 the shaft I will be turned, and the crank i, link or pitman J, and cross-bar K, moving with said shaft, will force down the arms h and their attached jaws H to the clamping position indicated in Fig. 15 6, when the crank i will be just past the dead-center, and its farther rearward movement be prevented by the contact of the link or pitman J with the post E, as shown in Fig. 6, 20 and thus, owing to the position of said crank, the jaws H will be retained in the said clamping position by the resilience of the spring-arms h, which yield to allow the crank to pass the dead-center. If the button-hole has not 25 yet been cut, this will next be done by the proper cutter; but in working holes which have been cut in advance the hole can be spread the instant the clamping-lever has been depressed by moving the spreading-lever 30 D forward in the direction indicated by arrow 2 in Fig. 3, and this movement of the said lever D can be effected by the same movement of the hand of the operator by which the clamping movement of the lever L is accomplished, 35 these two levers both turning on horizontal pivots and both moving forward or in the same direction in clamping and spreading the button-hole. The forward movement of the lever D forces the slide C backward, and the inclined ribs c on the latter, working in the inclined groove b of the plates or lower clamping-jaws, B, move said jaws outward or away from each other, and thus effect the spreading of the button-hole, the outward movements 40 45 of said plates or jaws B and of the upper jaws, H, which are mounted thereon and rigidly connected laterally therewith, being uniform throughout, so that said jaws will remain parallel with each other at all times, and thus 50 spread the button-hole evenly its entire length.

When the button-hole is finished, the work will be released and the clamping-jaws again moved together, as in Fig. 1, by turning the levers L and D in the direction opposite to that indicated by the arrow in Fig. 3, the upper clamping-jaws being lifted positively by the cross-bar K, and the inward movements of the plates or jaws B being also effected positively by the rib-and-groove connection 55 of said plates and the slide C. By making all of these movements positive I am enabled to dispense with springs heretofore employed to effect reverse or return movements in this class of devices, these springs being objectionable 60 by reason of their liability to break or to lose their force after considerable use.

It is obvious that the rib-and-groove connection of the plates B and slide C might be reversed by forming the ribs on the former and the grooves in the latter; or instead of these ribs other projections—as pins with or without rollers working in inclined or diagonal slots—might be employed.

I claim as my invention—

1. In a button-hole clamp, the combination, 75 with the base-plate and the upper and lower clamping plates or jaws adapted to move laterally thereof, of a spreading-slide having rib-and-groove connections with the said lower plates or jaws, substantially as set forth. 80

2. In a button-hole clamp, the combination, with the base-plate having parallel guides, of two lower plates or clamping-jaws adapted to slide laterally on said base-plate in said guides, two upper clamping-jaws mounted on 85 and rigidly connected with said lower plates or jaws, and a slide for moving the latter plates from or toward each other, substantially as set forth.

3. In a button-hole clamp, the combination, 90 with the base-plate and the upper and lower clamping plates or jaws adapted to move laterally thereof, of a spreading-slide movable longitudinally of the said lower plates or jaws and having rib-and-groove connections there- 95 with, a spreading-lever connected with said slide, and a clamping-lever connected with the said upper jaws, both of said levers being movable in the same direction in performing their respective functions, substantially as set 100 forth.

4. The combination, with the base-plate and the upper and lower clamping-jaws, of a slotted cross-bar for operating the said upper jaws, a pitman, and a shaft having an arm or 105 lever and a crank, whereby the said upper jaws may be positively lifted and forced down, substantially as set forth.

5. The combination, with the base-plate and the lower plates or jaws, of blocks rigidly 110 fixed thereto, plates hinged to said blocks, arms carrying the upper clamping-jaws rigidly attached to said plates, a shaft journaled in said blocks and having an arm or lever and a crank, a cross-bar engaging the said arms 115 of the clamping-jaws, and a pitman or link connecting said cross-bar and crank, substantially as set forth.

6. In a button-hole clamp, the combination, with the base-plate, the upper and lower 120 clamping plates or jaws, the spring-arms by which the upper jaws are carried, and the cross-bar engaging said arms, of a shaft having an arm or lever and a crank, a pitman or link, and a post with which the latter is in 125 contact when the upper jaws are in clamping position and the said crank is past the dead-center, substantially as set forth.

7. The combination, with the base-plate and the lower and upper clamping-jaws, of a slotted cross-bar, through which the spring-arms 130 of the latter loosely pass, regulating-screws on

said cross-bar for varying the stress of said arms, and devices for raising and lowering said cross-bar, substantially as set forth.

8. In a button-hole clamp, the combination, 5 with the base-plate and the lower clamping plates or jaws mounted loosely thereon and provided with inclined grooves or slots, of a spreading slide having projections fitting in

said grooves or slots, substantially as set forth.

In testimony whereof I affix my signature in presence of two witnesses.

JAMES G. GREENE.
